MULTI-FRAME PRESS

John M. Hausman, Stow, Ohio

Application October 23, 1956, Serial No. 617,828

1 Claim. (Cl. 100—194)

This invention relates to relatively large heavy presses, such as are used in the rubber or plastic industry, especially to a press characterized by the provision of a plurality of vertically extending, spaced, parallel frame plates to provide a multi-frame press having desirable properties.

Heretofore there have been many different types of presses proposed of the type referred to and many styles of presses have been built and sold commercially in large quantities. These presses, as is well known in the trade, have relatively high pressures set up therein and in general, the presses are of a heavy, massive construction so as to stand the forces exerted thereon and to give effective service life.

The general object of the present invention is to provide a new and improved type of a press of the class described characterized by the provision of a plurality of spaced, parallel press frame plates suitably secured together to form a unitary frame structure therefrom.

Another object of the invention is to provide a press frame made from a plurality of rolled plates having center apertures cut therefrom and with no metal castings being required in the frame.

Another object of the invention is to tie together a plurality of parallel, spaced frame plates, in a press frame, by a pair of laterally directed plates welded or otherwise secured to all of the press frame plates at opposite ends of a center opening provided therein.

Yet another object of the invention is to provide a stronger, but lighter, type of a press frame particularly adapted to have the required strength therein at the load carrying portions thereof.

Yet another object of the invention is to provide a beam-type frame from vertical and horizontal plates suitably secured together to form a unitary frame assembly therefrom.

Other objects of the invention are to provide a press frame particularly adapted to be built up readily from pre-formed rolled metal plates and with the frame members being designed for and secured together in proper relationship for individual press loads and requirements; and to provide special types of adjustable guides in a press frame for both vertical and lateral adjustment therein for engaging movable bolster means positioned by the press.

The foregoing and other objects and advantages of the invention will be made more apparent as the specification proceeds.

In order to understand the invention more completely, reference should be had to the accompanying drawings, wherein:

Fig. 1 is a front elevation of the multi-frame press embodying the principles of the invention; and

Fig. 2 is a side elevation of the press of Fig. 1.

When referring to corresponding parts shown in the drawings and referred to in the specification, corresponding numerals are used to facilitate comparison therebetween.

2

Generally speaking, the press of the invention comprises a plurality of spaced parallel flat frame plates made of rolled steel with each plate having a large center opening therein, tie plates welded to and extending between

5 all of said frame plates at opposed margins of the center openings, plate means welded to and extending between the frame plates at opposed ends thereof and lying parallel to the tie plates for reenforcing action, guide means positioned between and extending longitudinally of the frame 10 plates intermediate pairs of the spaced frame plates to engage bolster means in the press, and means for adjusting the guide means in the press.

Attention now is particularly directed to the details of the structure shown in the drawings, and a press 1 is 15 indicated in the drawings and comprises a plurality of metal frame plates 2, 2 that extend vertically of the press 1 in parallel, evenly spaced relationship. These metal frame plates 2 are preferably made from rolled metal sheets, usually steel, and the plates are of generally 20 rectangular shape. Each of the frame plates 2 has a substantially rectangular center opening 3 provided therein with such openings being provided, for example, by burning or otherwise cutting portions of the frame plates therefrom.

25 The frame structure for the press 1 is at least partially formed by a pair of flat metal top and bottom tie plates 4 and 5, respectively, that are positioned at the opposite vertical margins of the center openings 3 in the plates 2.

30 The top tie plate 4 and the bottom tie plate 5 are welded, for example, to each and every one of the frame plates 2 for securing them together and effectively transferring load therebetween. The frame structure for the press 1 includes a plurality of spacer plates 6 that are positioned intermediate adjacent pairs of the frame plates 2, 2 ad-

35 jacent the top portion thereof and which spacer plates 6 can be welded or otherwise suitably secured to the adjacent frame plates for reenforcing the plates and making a unitary structure therefrom. Figs. 1 and 2 of the draw-

As another feature of the invention, the bolster 10 has pairs of guide blocks 12 secured to opposite lateral or marginal portions thereof and which guide blocks are adapted to engage with specially positioned guide means provided by the invention. Such guide means comprise angles 13 which extend vertically of the press 1 intermediate pairs of the frame plates 2. These angles or positioning means secured thereto have suitable slots (not shown) therein to permit slight adjustment for the guide angles 13 inwardly or outwardly laterally with relation to the press 1 by adjustment of the control means provided therefor. Such slots engage threaded rods 14 which extend between adjacent pairs of the plates 2 and are welded or otherwise suitably secured thereto. These rods 14 position the angles 13 in desired adjustment front to rear of the press frame 2, as shown in Fig. 2 of the drawings. The rods 14 have lock nuts 15 provided thereon for positioning and holding the guide angles 13 in a fixed position after proper adjustment thereof has been made. Adjustment in the position of these guide angles 13 laterally inwardly and outwardly of the frame means is controlled by a pair of adjusting screws 16 that engage each of the guide angles 13 adjacent opposite ends thereof and which in turn are positioned by slots 17 provided in guide bars 18 suitably secured to and extending between pairs of the metal frame plates 2, 2 as best shown in Fig. 2 of the drawings. Suitable lock nuts 19 engage with these screws 16 for aiding in retaining them in a given position on the positioning bars 18 so that the guide angles 13 can be adjusted both laterally in the press 1 as well as from front to rear thereof to compensate for wear in the guide blocks 12, or similar members that engage these guide angles to position the bolster 10 accurately in the press 1.

Additional reenforcing plates 20 may be secured to 35 and extend between and adjacent pairs of the plates 2, immediately above the top plate 4, if desired.

From the foregoing, it should be observed that a desirable type of a press has been provided by the invention and that such press is made from a plurality of 40 rolled metal plates which have center openings cut or otherwise formed therein and that no cast members need be used in the press. In addition, the frame of the press 1 is of an open beam type construction which provides a maximum of strength with a minimum of weight and 45 with a minimum overall size in the press. The frame plates can be varied in thickness and/or spacing for vary-

ing strength requirements. By the open frame structure provided, it is possible to mount guide means in a novel adjustable manner in the press so that an additional novel structure and functioning is provided in such press. Thus the objects of the invention are achieved.

While one complete embodiment of the invention has been disclosed herein, it will be appreciated that modification of this particular embodiment of the invention may be resorted to without departing from the scope of the invention as defined in the appended claim.

What is claimed is:

In a press, a plurality of spaced parallel flat frame plates of rolled steel each with a large center opening therein, tie members welded to and extending between all of said frame plates at opposed margins of said center openings, reenforcing means welded to and extending between said frame plates at one end thereof and lying parallel to said tie members, and reenforcing means welded to and connecting said frame plates at the opposite end thereof, bolster means received in said center openings, guide angles extending longitudinally of said frame plates intermediate pairs of said frame plates to position said bolster means in the press, rods extending in the direction of from front to rear of the press between pairs of said frame plates adjacent said center openings therein, means securing said guide angles to said rods for adjustment front to rear of the press, and means engaging said guide angles and carried by the same frame plates at said rods for adjusting said guide angles laterally of the press.
